UNITED STATES PATENT OFFICE.

FREAN A. MABEE, OF ST. LOUIS, MISSOURI, AND JULIUS F. ZETZSCHE, OF RICHVIEW, ILLINOIS.

DESIGN FOR A MEAT-PAN.

SPECIFICATION forming part of Design No. 25,106, dated January 28, 1896.

Application filed December 27, 1895. Serial No. 573,476. Term of patent 7 years.

To all whom it may concern:

Be it known that we, FREAN A. MABEE, of the city of St. Louis, State of Missouri, and JULIUS F. ZETZSCHE, of the city of Richview, 5 county of Washington, and State of Illinois, have invented a new and original Design for a Meat Roasting and Basting Pan, of which the following is a full, clear, and exact description, reference being had to the accompanying drawing, forming a part hereof.

In the drawing, the figure is a view in perspective of our improved meat roasting and basting pan.

The leading feature of our design consists 15 of a rectangular base or body surmounted by a perforated semicylindrical body.

1 indicates a rectangular base or body, from the center of which rises a semicylindrical body 2, the same being provided with the perforations 3.
